ELECTRIC SWITCH

Tomlinson F. Johnson, Atlanta, Ga.

Application May 12, 1938, Serial No. 207,596

10 Claims. (Cl. 200—48)

This invention relates to high tension electric switches and, among other objects, aims to provide greatly improved articulated swinging switch arms or blades having means to operate them in such manner as to produce powerful leverage for opening and closing them, thereby enabling high pressure contacts to be employed and permitting easy operation even when the contacts are corroded or covered with ice. The main idea is to provide improved articulated switch arms and blade tips capable of initiating opening movement by striking an effective hammer blow and, thereafter, imparting compound longitudinal and swinging movement to the tips.

Other aims and advantages of the invention will appear in the specification, when considered in connection with the accompanying drawings, wherein:

Fig. 1 is a side elevation of a switch unit of the rocking insulator type embodying the invention;

Fig. 2 is a fragmentary enlarged top plan view of Fig. 1;

Figs. 3, 4 and 5 are enlarged side elevations showing the blade tip in different operated positions;

Fig. 6 is a side elevation of a rotating insulator switch embodying the invention; and

Figs. 7 and 8 are fragmentary, enlarged top plans, partly in section, showing two positions of the blade tip.

Referring particularly to the drawings and to the rocking insulator switch unit shown in Figs. 1 to 6, inclusive, the switch structure is shown as being supported on an ordinary structural channel 10 carrying a stationary insulator 11 on which the spring switch jaws 12 are mounted. A rocking insulator 13 having the usual operating arm 14 is also mounted on the channel and carries a rigid switch arm 15 bolted to its cap. A blade tip 16 is shown as being connected to the arm 15 by pairs of spaced links 17 and 18, with its rear end portion overlapping and spaced from the forward end of the arm.

Referring to the link mechanism, the two forward links 17 on opposite sides of the arm and tip are connected to them by pivot pins 19 and 20, the latter extending through a vertically elongated slot 21 in the arm 15 to provide for a slight lost motion when the switch arm is initially raised and the contact is corroded or frozen. The rear links 18 are connected to the tip and arm by pivot pins 22 and 23, the distance between the pivot pins 20 and 23 being much shorter than that between the pivot pins 19 and 22; that is to say, the links diverge upwardly. The up-

per pin 22 extends through a horizontally elongated slot 24 in the rear end of the blade tip and the rear end of the tip also has an integral downwardly extending lug 25 adapted to engage the top edge of the arm 15 when the switch is closed, as shown in Fig. 3. Each of the links 18 also has a rearwardly extending arm 26 assuming the form of an ordinary bell crank. These arms have integral stub pins 27 to carry tension springs 28 which are connected at their forward ends to the end portions of the pins 20 projecting beyond the sides of the forward links 17. The arrangement is such that the switch arm and blade tip are substantially rigid when the switch is closed and the contact end 29 of the tip rests on the shelf 30. The lug 25, contacting the top edge of the arm 15 when the switch blade is in this position, limits the downward swinging movement of the blade; while the springs tend to break the joint and move the blade tip to the position shown in Fig. 5. However, the spring jaws, which may be far more powerful than those of ordinary switches, prevent any such movement.

The forward end of the arm 15 is shown as terminating in a curved horn 31 acting as a stop member against the lower edge of the tip 16 slightly in advance of the pivot pin 19, the arrangement being such that this horn and the two links hold the tip and arm in the positions shown in Fig. 5 after the tip has been initially moved to that position. Further movement beyond that position will be imparted to both the arm and the tip as if they were a rigid unit.

Referring now to the operation of the switch, assuming that the contact is corroded or frozen, it will be noted that initial swinging movement imparted to the arm 15 as shown in Fig. 4, will swing the links 17 and 18 so that the rear ones will move rearwardly and the upper pivot pin 22 will strike the bottom or rear end of the elongated slot 24, thus imparting a hammer blow to the rear end portion of the tip and tending to swing it both rearwardly and upwardly at the same time. This is most effective because of the length of the lever arm between the pivot pin 22 and the contact end 29 of the tip. At the same time, the vertical slot 21 at the forward end of the arm 15 moves upwardly until the pivot pin 20 is seated in the bottom of the slot. This initial movement stretches the springs 28 and, when the hammer blow breaks the frozen contact, they act to move the pivot pins 20 and 22 back to their original positions in the respective slots, as shown in Fig. 3. Further upward

movement of the arm 15 will impart a compound longitudinal and upward swinging movement to the blade tip through the links until the horn 31 strikes the bottom edge of the tip, as shown in Fig. 5, and completion of the opening movement will be accomplished as a unit. Incidentally, when the horn 31 strikes the bottom edge of the tip a slight hammer blow it will start the contact end 29 of the tip on its backward movement out of the top of the jaws. When the blade is swung to closed position it will be seen that powerful endwise pressure is applied to the tip, due to the lever action.

Referring now to the modified form of switch shown in Figs. 6, 7 and 8, the switch unit is supported on the usual channel 40 carrying the stationary insulator 41 on which the jaws 42 are mounted to receive the switch blade when swung in a horizontal direction, the jaws being identical with those shown in the other form of switch. A rotating insulator 43 having an operating arm 44 is mounted on the other end of the channel 40 and carries a rigidly connected, horizontally swinging arm 45, conveniently in the form of a piece of copper pipe. The forward end of the arm 45 is shown as carrying a fitting 46 to which a blade tip 47 is connected by means of pairs of toggle links 48 and 49. In this instance, the fitting 46 has a flattened forward end 50 and the toggle links 48, parallel with the axis of the switch arm, are connected to the rear end of the tip and the flattened portion 50 on the arm by pins 51 and 52 without any lost motion. The other links 49 are connected at their rear ends to the flattened end 50 by a pin 53 which is arranged fairly close to the pin 52 and these links diverge forwardly and outwardly from the links 48, being connected by a pin 54 to the tip through a laterally extending, elongated slot 55. In this instance, a pair of tension springs 56 are connected between the outer ends of the pin 52 and a pin 57 which extends through an ear on the back side of the blade tip, the axis of said springs being shown as parallel with the longitudinal axis of the links when the blade is in closed position, as best shown in Fig. 7. The forward end of the flattened portion 50 on the fitting 46 cooperates with a rearward stop projection or nose 58 on the rear end of the tip to provide a stop to limit the closing movement of the jointed ends when the contact portion 59 of the tip strikes the shelf 60, the parts assuming a stiff leg position shown in Fig. 7. The forward end of the arm or the fitting is also shown as having an angularly extending horn 61 which acts as a stop to strike against a shoulder 62 on the tip when the parts are swung to the position shown in Fig. 8 so that the tip and arm may move as a unit to open the switch.

Referring now to the operation of this modified form of switch, it will be noted that initial clockwise movement of the switch arm 45, as viewed in Fig. 7, will tend to break the toggle joint between its forward end and the tip. If the contact is free, however, the tension of the springs 56 will assist in swinging the arm and tip to the position shown in Fig. 8, with the pivot pin 54 for the links 49 still remaining in the bottom or back portion of its elongated slot 55. However, if the contact is corroded or frozen over, the tip will remain in its closed position and the forward end of the arm will then swing relative to the rigid rear end of the tip. This initial movement will break the stiff leg or knee joint and cause the pin 54 at the forward ends of the links 49 to move toward switch opening position and strike the

forward or front ends of the elongated slot 55, thus imparting a hammer blow to the rear end portion of the tip 47 and moving it slightly rearwardly and at the same time in an arcuate path to loosen the contact. Further movement of the arm 45 will swing the rear end of the tip to the position shown in Fig. 8 until the horn 61 strikes the stop shoulder 62 on the tip when the arm and tip will move as a unit to the fully opened position.

It is not necessary to describe the action of the links during closing movement of either form of switch. It is sufficient to state that their closing movements are the reverse of the opening movements and the final movement is imparted with very powerful leverage so that great spring pressure can be applied to the jaws, thus providing the best possible contact.

From the foregoing description, it will be seen that the invention provides greatly simplified and very effective switch units capable of being used in the coldest climates and the operation is as easy as that of ordinary switches for the same purpose. There are no delicate parts which require replacement and after the toggle joints are made, it is not necessary to make any further adjustments.

Obviously, the present invention is not restricted to the particular embodiments thereof herein shown and described. Moreover, it is not indispensable that all the features of the invention be used conjointly, since they may be employed advantageously in various combinations and sub-combinations.

What is claimed is:

1. In a high tension electric switch of the class described, a vertically swingable blade comprising an arm; a tip portion pivotally mounted on said arm; spaced pairs of links forming a part of said pivotal connection holding the arm and tip normally spaced and having a slight lost motion relative to the tip; and a spring connection between the arm and the tip to take up the lost motion and permit the arm to contact with and impart a hammer blow to the tip when it is stuck in the switch jaws and the arm is initially moved toward switch opening position.

2. In a high tension electric switch of the class described, a swinging articulated blade comprising an arm; a blade tip having its rear end overlapping and slightly spaced from the forward end of said arm; and spring urged links having a slight lost motion connecting the arm and tip, so arranged as to cause the arm to impart compound swinging and endwise movement with powerful leverage during the initial opening and final closing movement of the arm.

3. In a high tension electric switch of the class described, a swinging articulated blade comprising an arm; a blade tip having its rear end overlapping the forward end of said arm; and spaced pairs of links pivotally connecting the arm and tip in spaced relation with a slight lost motion and so arranged that the arm imparts compound swinging and endwise initial opening movement to the tip with powerful leverage and the arm will move relative to and strike the tip with a hammer blow, if it is stuck when the arm swings toward open position.

4. In a high tension electric switch of the class described, a vertically swingable blade comprising an arm; a blade tip having its rear end overlapping the forward end of said arm; spaced pairs of links pivotally connecting the arm and tip in spaced relation with a slight lost motion and arranged to cause the end portion of the arm to

strike the tip with a hammer blow when the tip is stuck; and means on the arm to engage the tip beyond the link connections after the initial opening movement is imparted to the tip to cause the arm and tip to complete the opening movement as a unit.

5. In a high tension electric switch of the class described, a swinging articulated blade comprising an arm and a blade tip having its rear end overlapping the forward end of said arm; spaced pairs of links pivotally connecting the arm and tip holding their overlapping ends normally spaced from each other and arranged to impart compound swinging and endwise initial opening movement to the tip with powerful leverage when the arm swings toward open position; said links having slotted connections permitting the arm to swing into contact with the tip when the tip is stuck and impart a hammer blow to loosen the tip; means on the arm to engage the tip beyond the link connections after the initial opening movement is imparted to the tip to cause the arm and tip to complete the opening movement as a unit; and stop means between the rear end portion of the tip and the arm to limit the relative pivotal movement to the closed position.

6. In a high tension electric switch of the class described, a swinging articulated blade comprising an arm; a blade tip having its rear end overlapping the forward end of said arm; links connecting the arm and tip in spaced relation so arranged as to impart compound swinging and endwise movement with powerful leverage during the initial opening and final closing movement of the arm, said links having a slight lost motion permitting the arm to swing initially before the tip is moved and then contact with and impart a hammer blow to the tip when it is stuck in the jaws.

40. 7. In a high tension electric switch of the class described, a swinging articulated blade comprising an arm; a blade tip having its rear end overlapping the forward end of said arm; links connecting the arm and tip with their overlapping ends in spaced relation and so arranged as to impart compound swinging and endwise movement with powerful leverage during the initial opening and final closing movement of the arm, said links having a slight lost motion permitting the arm to

start its movement independently of the tip so that it will contact with and impart an initial hammer blow to the tip when it is stuck in the jaws and loosen the tip; and a tension spring between the tip and blade biasing them toward open position when the switch is closed and supplementing the power of the hammer blow.

8. In a high tension switch of the class described, a stationary insulator carrying powerful spring jaws; a rocking insulator having operating means; a blade mounted on said rocking insulator comprising a rigid arm and pivotally connected tip having spaced pairs of links pivoted to the blade and tip to permit the blade to close and to open initially with powerful leverage, one pair of 15 said links having a slight lost motion, whereby the arm can initially move into contact with and impart a hammer blow to the tip to loosen it when it is stuck in the jaws.

9. In a high tension switch of the class described, a stationary vertical insulator carrying powerful horizontal spring jaws; a rotating vertical insulator; a blade mounted on said rotating insulator for horizontal swinging movement; said blade carrying a tip; means to limit the closing 25 movement of the tip; and compound links providing a knee joint between the arm and tip normally holding them spaced apart and having a slight lost motion permitting the arm to swing initially and engage the tip to impart a hammer 30 blow to the tip when it is stuck in the jaws.

10. In a high tension switch of the class described, a stationary vertical insulator carrying powerful horizontal spring jaws; a rotating vertical insulator; a switch arm on the rotating in- 35 sulator connected to swing horizontally; a blade tip; spaced pairs of links pivotally connecting the arm and tip in spaced relation and arranged to impart compound swinging and endwise initial opening movement to the tip with powerful lever- 40 age when the arm swings toward open position; means on the arm to engage the tip beyond the link connections after the initial opening movement is imparted to the tip to cause the arm and tip to complete the opening movement as a 45 unit; and stop means between the rear end portion of the tip and the arm to limit the relative pivotal movement to the closed position.

TOMLINSON F. JOHNSON.
